UNITED STATES PATENT OFFICE.

OTTO EICK, OF ST. LOUIS, MISSOURI.

DESIGN FOR A RUBBER BRUSH.

49,764.

Specification for Design.

Patented Oct. 17, 1916.

Application filed July 22, 1916. Serial No. 110,806. Term of patent 14 years.

To all whom it may concern:

Be it known that I, Otto Eick, a citizen of the United States, residing at St. Louis, in the State of Missouri, have invented a new, original, and ornamental Design for Rubber Brushes, of which the following is a specification, reference being had to the accompanying drawing, forming part thereof.

The figure is a front elevation of a rubber brush, showing my new design.

I claim:

The ornamental design for a rubber brush, as shown.

OTTO EICK.
